UNITED STATES PATENT OFFICE.

WILLIE O. RANDLETT, OF RICHMOND, VIRGINIA, ASSIGNOR OF ONE-HALF TO CYRUS B. BUCHANAN.

DEVICE FOR CLEANING FLUME GRATINGS.

Application filed June 16, 1921. Serial No. 478,187.

To all whom it may concern:

Be it known that I, WILLIE O. RANDLETT, a citizen of the United States, residing at Richmond, in the county of Henrico and State of Virginia, have invented certain new and useful Improvements in Devices for Cleaning Flume Gratings, of which the following is a specification.

My invention relates to improvements in devices for cleaning flume gratings.

The object of my invention is to provide a device of this character which can be readily used in connection with any of the forms of gratings now used and in which a frame is used to travel up and down over the grating and having means for attaching different forms of rakes for cleaning the grating of different character of trash such as leaves, sticks or logs as the case may necessitate.

Another object of my invention is to provide a device of this character in which the different forms of rakes are interchangeable and so arranged that they may be held in such a position that the rake will readily descend past the trash and can be moved into a position to catch and raise the trash on its upward movement and can be dumped free of all trash or logs when in its raised position; and in which all operating parts are above the water line for inspection and repair.

Another object of the invention is to provide a cleaning device which may be carried along and used at different points of the grating and thus necessitate but one cleaner for any number of gratings leading to the turbines and also provide a cleaner in which all the operating parts are above the water line, thus preventing any possibility of the trash interfering with the operation of the device.

A still further object of my invention is to provide a simple cheap and effective device of this character having a wide range of operation and having certain details of structure and combination of parts herein-after more fully set forth.

In the accompanying drawings,

Figure 1, is a front view of a flume grating, showing the rake carrying frame in position with the log rake applied.

Figure 2 is a vertical sectional view of Figure 1.

Figure 3, is an enlarged perspective view

of the rake carrying frame showing the stop for the log rake removed.

Figure 4, is a front view of the rake carrying frame showing the trash rake in place of the log rake shown in Figure 1 of the drawings.

Figure 5, is a vertical transverse sectional view of Figure 4 of the drawings.

Figure 6, is a vertical sectional view similar to Figure 5 showing the rake hinged above and showing the basket applied for dumping the trash therefrom.

Figure 7, is a side view of the grating showing a form of rake carrying frame in which the rake travels directly on the rake bars.

Referring now to the drawings, 1 represents the grating of a flume for use in turbines or other water power plants and which are usually arranged in a series, one grating to each turbine. These gratings are of different width and are vertically disposed but in some instances they are obliquely arranged. At the ends of each are vertically or obliquely arranged to correspond with the grating, the channel irons 2 and 3 which extend parallel with the grating and in front thereof and which form guideways for the cleaner carrying frame as clearly shown in the drawings. The channel irons between the series of gratings are made of a double form to provide guides for the cleaner carrying frame for the grating on either side, it being understood that the one cleaner carrying frame is moved along and used to clean any of the gratings.

The cleaner carrying frame consists of L shaped end beams 4 and 5 having the rollers 6 and 7 mounted therein adjacent the upper and lower ends and which extend into the channel irons 2 and 3 and whereby the frame has a free vertical movement in the channel irons. The end beams 4 and 5 are connected at their upper end by the L shaped beams 8. The lower ends of the side beams 4 and 5 have rigidly connected thereto the outwardly extending L beams 9 and 10 which have their outer ends connected by the L beam 11 all of which as heretofore stated slides in the channel irons 2 and 3.

The beam 8 has in its upper face the eyes 12 and 13 to which are connected the cables 14 and 15 by means of which the frame is lowered or raised in the channel irons. It

will be understood that the cables 14 and 15 are attached to a movable crane or the like whereby it is moved along the flume grating and the frame can be lowered or raised in 5 position at any of the series of gratings whereby the one device can be used to clean all of the gratings.

The transverse beam 11 adjacent its ends is provided with the hinge members 16 and 17 which are of a double form as shown in 10 Figures 3, 5 and 6, so that the rake can be pivotally connected thereto in either position shown in Figure 5 or the position in Figure 6 of the drawings as will be herein- 15 after more fully described. As shown in the drawings the rake 17' consists of a rectangular frame made of angle irons and having the teeth 18 extending entirely across the same and have pointed outer ends. The side 20 irons 19 of said rake frame are provided with the two or more double hinge members 16 and 17 by means of bolts 21 in the position shown in Figure 5 of the drawings or pivotally connected by bolts in the position 25 shown in Figure 6 of the drawings, it being understood, that additional intermediate hinges may be applied if necessary.

When the rake is connected to the lower 30 position of the frame as shown in Figure 5 cables 22 are connected to the eye of the hinge 20 and extend upwardly around pulleys 23 mounted in the cross bar 3 of the frame and extend upwardly and are operated in any desired manner. These cables 35 in the downward movement of the frame are held taut so that the rake frame is held in approximately a vertical position as shown in Figure 5 so that in the downward movement of the frame the trash which hangs 40 close to and against the grating will not be engaged by the rake and a free downward movement of the rake carrying frame is permitted.

The rake at each end is provided with 45 eyes 24 to which are connected the cables 25 which extend upwardly around the pulleys 26 carried by the inner ends of the outwardly extending beams. These pulleys are set in the beam a short distance from the 50 ends thereof, so that the cables can not jump off of the pulleys. The cables 25 extend vertically from the pulleys and are operated in any desired manner from above. As heretofore stated the rake carrying frame 55 is lowered when the rake is in the position shown in Figure 5, it being held in this position by the cables 22. When the rake carrying frame has reached the lower ends of the guideways, the cables 22 are released 60 and the cables 25 cause the rake to swing outwardly until the rectangular frame is in a horizontal position abutting the lower end of the frame with the rake teeth 18 close to or extending slightly between the bars 65 of the grating but preferably spaced from

the bars. While the independent cables 14 and 15 heretofore described may be used for lowering and raising the rake frame, the entire operation of lowering and raising the rake frame and in operating the rake from 70 a vertical to a horizontal position is preferably controlled by the cables 22 and 25, the cable 25 being gradually released as the cables 22 are tightened, until the rake is brought to a vertical position when the 75 cables 22 will support the entire weight of the frame and holding the rake teeth away from the grating in the downward movement for the purpose heretofore described.

From this it will be seen that any deposit 80 of sand, mud or the like at the lower end of the grating is raked towards the grating in the movement of the rake from a vertical position to the horizontal position. The sand, mud or the like which is not taken up by the 85 rake is so agitated that the flow of water carries it through the flume grating and therefore the flume grating can not fill up above the base of the grating. When the rake frame has been moved to the horizontal 90 position the cables 25 are drawn up to maintain the rake in the horizontal position, and at the same time raise the rake frame above the grating, thus as will be seen, it carries up the trash which is held by the flow of 95 the water, and against the grating, and when above the grating can be readily emptied by releasing the cable 25, and the cables 22 gradually tightened.

The operating cables at the upper ends 100 are preferably attached in a vertical plane slightly within the face of the grating so that when the rake frame is raised above or free of the grating, the rake frame can be swung inward if desired and cleaned of 105 trash or logs by hand independent of the method of dumping by the cable or other means.

It often happens that logs accumulate 110 against the grating in which event the ordinary rake is removed by removing the bolts 21 and placing the log rake 26 pivotally connected thereto by the same bolts 21. This log rake consists of two L beams 27 and 28 to which are attached the rake teeth 29 which have their lower ends curved inwardly at 30 and which extreme ends are in a plane beyond the outer edge of the grating as shown in Figure 2 of the drawings. When using the log rake the plates 115 31 are bolted to the transverse beam 11 of the frame so that the rake can not move inwardly beyond the position shown in Figure 2 and thus the ends of the rake can not pass between the grate bars and catch on the 120 braces thereof. These plates are held by the removable bolts 32 so that they can be readily removed or replaced when desired as they have to be removed when the regular rake is used. The L beam 28 has rings 125 130

or eyes carried thereby to which are connected the cables 22 which extend upwardly over the pulleys 23 the same as heretofore described when using the other rake. The 5 inner face of the beam is provided with eyes or rings 34 to which are connected the cables which extend upwardly around the pulleys as heretofore described.

In using the log rake the frame is lowered 10 into the flume and the cables 22 having been kept taut to hold the rake bars 29 out in the position shown in dotted lines Figure 2. When the frame has reached its lowered 15 position the cable 22 is slackened and the cable 25 tightened to bring the rake bars 29 in the position shown in full lines Figure 2 and the frame is raised by the cables 22 and 25 heretofore described. The cables 25 are kept taut to hold the rake bars in this 20 position until the frame reaches its upper position when they are gradually released and the cables 22 are tightened to swing the rake bars in the position shown in dotted lines Fig. 2 and the logs, trash and the like 25 are dumped therefrom.

In the form shown in Figure 6 the rake 17 is pivoted above by the bolts 21 and normally remains in the horizontal position shown in Figure 6 with the rake teeth close 30 to the grating. In this form the cables 22 are connected to the upper pivot of the eye at 22' and in this form a pivoted basket 34 is carried by the inner end of the basket and normally rests flat thereon.

35 While I preferably operate the log rake as illustrated in Figure 2, the log rake can be reversed when hung from the bottom of the frame by removing the bolts 21 and turning the hooks outward, as will be readily understood.

In order to hold the rake in the position shown in dotted lines, Figure 6, I provide a 40 sliding bar 36 working in the guides 37 carried by the frame and adapted to engage and hold the rake in the position shown in 45 dotted lines Figure 6 as heretofore mentioned. This is essential to allow the free downward movement of the rake in lowering the same. In order to dump the basket 50 its upper edge is provided with a projection 38 at each end which extends in beyond the guideways and is adapted to engage the stops 39 carried by the guideways whereby 55 when the sliding frame has reached a certain point the basket is dumped as will be readily understood.

In the form shown in Figure 7 the three 60 forms of rakes and baskets may be employed and operated in the same manner as heretofore described, but the sliding frame does not work in guide ways adjacent the grating but the ends of the frame are provided with grooved pulleys 40 which roll directly 65 on the grating and whereby my device is designed to be used on any form of grating.

Having thus described my invention, what I claim and desire to secure by Letters Patent is:—

1. The combination with a grating of the character described, comprising a frame 70 sliding longitudinally of said grating, a pivoted reversible rake carried by the lower end of the frame, means for raising said frame, and means for rocking the rake on its pivot.

2. The combination with a grating of the 75 character described, comprising a frame sliding longitudinally of said grating, a pivoted reversible rake carried by the lower end of the frame, cables for raising and lowering the frame, and cables for rocking the rake 80 on its pivot.

3. The combination with a grating of the character described, comprising a frame 85 sliding longitudinally of said grating, means for pivotally connected rakes of different character to the lower end of the frame, means for raising and lowering said frame, and means for rocking the rake on its pivot.

4. The combination with a grating of the character described, comprising a frame 90 sliding longitudinally of said grating, means for pivotally connected rakes of different character to the lower end of the frame, positive means for holding the rake in either its inner or outer position, and means for 95 raising and lowering said frame.

5. The combination with a grating of the character described, comprising a frame 100 sliding longitudinally of said grating, a pivoted rake carried by the lower end of the frame, cables attached to the rake for holding it in a vertical position when the frame is lowered and cable attached to the opposite sides of the rake for moving it inwardly 105 in a horizontal position and holding it in said position during the upward movement of the frame.

6. The combination with a grating having guideways at the ends parallel therewith, a cleaner frame sliding in said guideways, a 110 rake adapted to be pivoted either to the lower or upper edge of the horizontal portion of the frame, to remain permanently in a horizontal position when pivoted to the upper edge or to swing in a vertical position 115 when pivoted to the lower edge and means for operating said pivoted rake.

7. The combination with a grating having guideways at its ends parallel therewith a cleaner frame sliding in said guideway, a 120 rake adapted to be pivoted to the upper or lower edge of the horizontal extension of the frame and a basket pivoted to the rake when pivoted to the upper edge and adapted to lay flat upon the rake, means for holding the 125 rake and basket in a tilted position and means carried by the guideways for engaging the basket and tilting it, in its upward movement.

8. The combination with a grating having 130

guide ways at its ends parallel therewith a cleaner frame sliding in said guide way, a pivoted rake carried by the frame, a basket pivoted to the upper face of the rake a lock for holding the rake and basket in its tilted position, projections carried by the basket and extending upwardly opposite the guideways and stops carried by the guideways and adapted to engage the projections and tilt the basket in its upward movement.

9. The combination with a grating of the character described, having guideways at its ends parallel therewith, a frame sliding therein, a log rake pivoted to the frame, stops to limit the inward movement of said rake, means for holding the rake in its limit of inward movement, means for holding the rake in its outward position and means for raising and lowering the frame.

10. The combination with a grating of the

character described, having guideways at its ends parallel therewith, a frame sliding in said guideways, means for pivotally connecting either a log rake or a trash rake to the frame, stops to limit the inward movement of said rake, means for holding the rake in its limit of inward movement, means for holding the rake in its outward position and means for raising said rake.

11. The combination with a grating of the character described, having guideways at its ends parallel therewith, a frame sliding therein; a log rake adapted to be pivoted to the frame, stops to limit the inward movement of said rake when the teeth extend towards the grating, means for raising and lowering said frame.

In testimony whereof I affix my signature.

WILLIE O. RANDLETT.
